CLAIM

The ornamental design for a push button handle, as shown and described.

DESCRIPTION

FIG. 1 is a perspective view of a first embodiment of a push button handle for use on, for example, a vehicle door.

FIG. 2 is a left side elevation view of the handle shown in FIG. 1.

FIG. 3 is a right side elevation view of the handle shown in FIG. 1.

FIG. 4 is a front end elevation view of the handle shown in FIG. 1.

FIG. 5 is a rear end elevation view of the handle shown in FIG. 1.

FIG. 6 is a top plan view of the handle shown in FIG. 1.

FIG. 7 is a bottom plan view of the handle shown in FIG. 1.

FIG. 8 is a perspective view of a second embodiment of a push button handle for use on, for example, a vehicle door.

FIG. 9 is a left side elevation view of the handle shown in FIG. 8.

FIG. 10 is a right side elevation view of the handle shown in FIG. 8.

FIG. 11 is a front end elevation view of the handle shown in FIG. 8.

FIG. 12 is a rear end elevation view of the handle shown in FIG. 8.

FIG. 13 is a top plan view of the handle shown in FIG. 8; and,

FIG. 14 is a bottom plan view of the handle shown in FIG. 8.

The broken lines shown represent portions of the push button handle that form no part of the claimed design.
